UNITED STATES PATENT OFFICE.

HENRY BONAWITZ, OF BROOKLYN, NEW YORK.

HEEL.

Application filed December 16, 1921 Serial No. 523,160.

To all whom it may concern:

Be it known that I, HENRY BONAWITZ, a citizen of the United States, residing at Brooklyn, in the county of Kings and State 5 of New York, have invented certain new and useful Improvements in Heels, of which the following is a specification.

This invention relates to rubber heels, and it comprises a heel having a dove tail 10 projection formed on the upper surface, and a shoe having a lift provided with an opening to receive the projection on the heel, the opening being smaller at the bottom than at the top, whereby the heel is locked therein 15 when assembled.

An object of the invention is the provision of means for positively retaining a rubber heel on a shoe without the use of nails, screws or other metallic fasteners.

20 When a rubber heel is nailed to a shoe or secured by other similar metallic fasteners, the rubber forming the heel wears faster than the metal, eventually exposing the metal and causing the nail to be forced through 25 the shoe. The exposed head of the nail also tends to injure floors, tear carpets, and otherwise damage property.

In the present invention, I provide a shoe 30 lift having a dove tail opening small at the outside. The heel is provided with a dove tail projection adapted to be received in this opening. When the heel is to be applied, it is first compressed and then forced into the 35 opening, immediately expanding and filling the opening. This causes a positive lock and prevents accidental displacement of the heel.

In the accompanying drawings, I have shown one embodiment of the invention. In this showing:

40 Figure 1 is a plan view of the bottom of a shoe showing the heel applied,

Figure 2 is a perspective view of the heel removed,

Figure 3 is a similar view of the bottom 45 of the shoe,

Figure 4 is a sectional view on line 4—4 of Figure 1, showing the heel removed, and,

Figure 5 is a sectional view on line 5—5 50 of Figure 1.

Referring to the drawings, the reference numeral 1 designates the bottom of a shoe. The rear portion of the shoe is provided with a lift 2 which is secured thereto in any suitable manner, as by nails 3. This lift is provided with a central opening 4. As

shown, the opening is dove tailed in shape, the walls 5 tapering inwardly toward the bottom. The exact taper of the walls forms no part of the present invention and variations in degree may be resorted to, but I have found that the size of the top 6 of the opening should be about one-quarter of an inch greater than the size of the bottom 7. The walls 5 are thus inclined about one-eighth of an inch from the perpendicular. A heel 8 is adapted to be secured to the lift, the heel being provided with a projection 9 on its upper surface. The projection is dove tailed in shape, the walls 10 inclining 65 upwardly and outwardly. The shape of the projecting portion of the heel thus corresponds to the opening in the lift. The projection, however, is of slightly greater size than the size of the opening in the lift. As 70 shown in Figure 4 of the drawings, the small area of the projection is slightly greater than the small part of the opening, denoted by line 7, and the top 11 of the projection is slightly larger than the top 6 of the opening adjacent the shoe. The body portion of the heel is also concave, the top 12 and bottom 13 being curved as shown.

In assembling the heel, the projecting portion 9 is compressed by suitable machinery 85 and is forced into the opening 4 in the lift. The heel is then forced into place by exerting a pressure on the bottom and forcing it toward the shoe. The size of the projecting portion 9 being slightly greater than the 90 opening in the sole of the shoe, maintains the projecting portion under compression when in place. This furnishes an additional securing means to prevent accidental displacement, and the wedge shaped projecting portion is prevented from moving outwardly 95 through the smaller, outer face of the opening 4. When the center of the heel is forced inwardly, the body portion of the heel is sprung to arrange the top and bottom thereof in a straight line, as shown in Figure 5 of the drawings. This creates a gripping action, due to suction around the top 12 of the heel, between it and the lift 3.

By use of suitable machinery for compressing the projection 9, the heel may be very rapidly placed in position on the shoe, which is a decided advantage over present methods wherein a plurality of nails must be independently driven into place to hold the heel 110 in position.

As stated, the elimination of nails or other

metallic fastening elements which will be exposed when the heel becomes worn is an advantage to the wearer and is an advantage to owners of property, such as public building and other places where flooring is marred by nails in the shoes of patrons.

To remove the heel, it is merely necessary to insert a knife above the body portion and cut it from the projection. The projection 10 may then be lifted from the hole 4 by means of a screw-driver or other tool.

The positive grip obtained by means of the wedge shaped projection and similarly shaped opening in the lift is much stronger 15 than the grip obtained by the use of nails and similar fasteners, and accidental displacement of the heel in wearing is prevented.

It is to be understood that the form of my 20 invention herewith shown and described is to be taken as a preferred example thereof, and that various changes in the shape, size, and arrangement of parts may be resorted to without departing from the spirit of the 25 invention or the scope of the subjoined claims.

I claim:

1. A shoe heel comprising a pair of members including a lift and a compressible

member, one of said members being provided with a polygonal opening having the edges of two opposite sides substantially straight and inclined toward each other, the walls of said opening being substantially flat and so inclined from the vertical that said opening has its greatest area remote from the other member, said other member being provided with a projection adapted for insertion in said opening, said projection being of similar form to but of slightly greater 40 area throughout than said opening and being of a thickness slightly less than said opening.

2. A shoe heel comprising a pair of members including a lift and a compressible member, 45 one of said members being provided with a polygonal opening having the edges of two opposite sides inclined toward each other, said opposite sides being substantially plane surface and so inclined from the vertical that 50 said opening has its greatest area remote from the other member, said other member being provided with a projection of a shape similar to said polygonal opening and adapted to be slidably inserted therein.

In testimony whereof I affix my signature.

HENRY BONAWITZ.
